Fig. 17

FIG. 1 is a top plan view of a reed switch envelope showing my new design;

FIG. 2 is a bottom plan view thereof;

FIG. 3 is a right side elevational view thereof;

FIG. 4 is a front elevational view thereof;

FIG. 5 is a top plan view of a modified form of the reed switch envelope described in FIG. 1 showing my new design;

FIG. 6 is a bottom plan view thereof;

FIG. 7 is a right side elevational view thereof;

FIG. 8 is a left side elevational view thereof;

FIG. 9 is a top plan view of a modified form of the reed switch envelope described in FIG. 1 showing my new design;

FIG. 10 is a bottom plan view thereof;

FIG. 11 is a right side elevational view thereof;

FIG. 12 is a top plan view of a modified form of the reed switch envelope described in FIG. 1 showing my new design;

FIG. 13 is a bottom plan view thereof;

FIG. 14 is a right side elevational view thereof;

FIG. 15 is a top plan view of a modified form of the

reed switch envelope described in FIG. 1 showing my new design;

FIG. 16 is a bottom plan view thereof;

FIG. 17 is a right side elevational view thereof.

The sides opposite to the sides shown in FIGS. 3, 11, 14 and 17 are identical to these respective figures. The end view opposite to the end view shown in FIG. 4 is identical with this figure.

I claim:

The ornamental design for a reed switch envelope, as shown and described.
